UNITED STATES PATENT OFFICE.

WILLIAM C. ANDERSON, OF LANSING, MICHIGAN, ASSIGNOR TO AMERICAN CUT GLASS COMPANY, OF LANSING, MICHIGAN, A CORPORATION OF MICHIGAN.

DESIGN FOR A DISH.

No. 38,950.

Specification for Design.

Patented Dec. 17, 1907.

Application filed October 5, 1907. Serial No. 396,119. Term of patent 7 years.

To all whom it may concern:

Be it known that I, WILLIAM C. ANDERSON, a citizen of the United States of America, residing at Lansing, in the county of Ingham and State of Michigan, have invented a certain new, useful, and Ornamental Design for Dishes, of which the following is a specification, reference being had therein to the accompanying drawings, forming part thereof.

The figure is a plan view of a dish, showing my new design.

I claim:

The ornamental design for a dish, as shown.

WILLIAM C. ANDERSON.
